United States Patent Office

Des. 184,033
Patented Dec. 2, 1958

184,033

POWDER BOX UNIT

John McD. Webb, Saint Thomas, Virgin Islands, assignor to West Indies Bay Company, Minneapolis, Minn., a corporation of Minnesota

Application April 26, 1957, Serial No. 45,895

Term of patent 14 years

(Cl. D58—17)

FIG. 1

FIG. 2

Fig. 1 is a perspective view of a powder box unit embodying my new design; and

Fig. 2 is a top plan view of the same.

The other side of the powder box unit embodying my new design is substantially like the side shown in perspective view, Figure 1.

I claim:

The ornamental design for a powder box unit, as shown and described.
